UNITED STATES PATENT OFFICE.

G. W. WOOD AND L. O. WEBSTER, OF UTICA, NEW YORK.

CANAL-LOCK GATE.

Specification of Letters Patent No. 11,103, dated June 13, 1854.

To all whom it may concern:

Be it known that we, GEORGE W. Wood and LUCIUS O. WEBSTER, of the city of Utica, in the county of Oneida and State of New 5 York, have invented certain Improvements in the Means of Opening and Closing the Valve-Gates of Locks on Canals; and we do hereby declare that the following is a full, clear, and exact description of the construction and operation of the same, reference being had to the annexed drawing, making a part of this specification, in which—

10 A, B, is a perspective elevation of a single lock gate, C, D, being the frame of the principle gate; F, and G, the valve gates, and E, the balance beam.

15 The improvements herein intended to be described, are confined to the shackle bars H and I; the levers M, and N; and to their attachments and fixtures, the object of the 20 improvements being, to arrange the fixtures attached to the balance beam, through which the power is applied to move the valve gates, in such a manner as to facilitate as much as 25 possible the opening and closing of these gates, and to provide also the means of readjustment whenever any derangement shall take place, without being obliged to separate, or remove the fixtures.

30 In the annexed drawing it will be seen that the valve-gate F, is closed, and G, is open. If the lever N, should be raised, and thrown over by the side of the lever M, the gate G, would be closed also. But if instead of this lever M, should be raised, and 35 thrown over by the side of the lever N, the gate F, would be opened, so that when the gates F, and G, are both open the levers M, and N, both lie together at N, each lever in 40 the movement making the sweep of a half circle.

45 It will be seen by a close inspection of the drawing that the levers M, and N, are similar, and that each is made hooked at the end which is connected with the shackle bar; the fulcrum, or point of gyration being at O; and the said connection with the shackle bar being at P. The upper end of each shackle bar is also bent, as seen at I, and H, so that 50 when the levers are thrown over in closing, both lying together on the side M, the point of connection P, in each is carried past its fulcrum O; and the tension of the rods K, and L, occasioned by any tendency of the 55 valve gates F, and G, to open, pulling either directly upon the fulcrum O, or upon a line

back of it, will not raise the levers, and consequently the valve-gates will not be opened. On the other hand, if the levers M, and N, or either of them is thrown at the side N, 60 in opening, the point of connection P, will be left at the right, or back of the fulcrum O, and the tension of the valve rods occasioned by a tendency of the valve-gates to close pulling either directly upon the fulcrum O, or upon a line back of it, will not move the levers, and consequently the gates will not be closed. No fastening, therefore, of the levers M, and N, to prevent the opening or closing of the valve gates, is necessary. By this arrangement the levers M, and N, either when the valve gates are opened 70 or closed, are thrown into a horizontal position, lying at the side of the balance beam, entirely out of the way of the tow line 75 sweeping across the lock as it often does, or of any other interfering object. By this arrangement also an extent of vertical movement of the valve rods K, and L, for the effectual opening and closing of the valve 80 gates is obtained equal to the whole diameter of a circle, the radius of which is of the length from O, to P; and this with the advantage of the short leverage O, P, against the power exerted, which extent of movement 85 could not be obtained by the use of straight levers, nor without a longer adverse leverage, and a corresponding increase of the requisite power. Nor could the horizontal position of the levers, both when the 90 gates are open and closed, be obtained by the use of straight levers, and the lifting from a point in the lever removed from its longitudinal line, and that point also thrown back of the fulcrum when the levers are at 95 rest for the purpose of locking them in their horizontal position, is thus obtained by simply bending the levers as here described.

99 The length of the valve rods K, and L, is of course so adjusted, as completely to close 100 the valve gates when the levers are in their proper horizontal position. But experience has shown that the great wear to which these fixtures are subjected in dirty water, soon occasions looseness, and leakage of the 105 valve gates. The valve rods must then be shortened, or the difficulty must be removed in some other way. For this purpose we have constructed the adjustable lever box R. It consists of the front plate R, and a 110 corresponding plate in the rear of it, both resting loosely at the ends in the stationary

head-blocks S, and T, which are bolted firmly to the balance beam. These plates are held together by the bearing bolts O, which form the fulcrums of the two levers 5 M, and N; or they may be otherwise bolted or secured; and the levers M, and N, move between them. They are also held in their position by the stationary bolts t, t, which being firmly fixed in the balance beam, project through vertical slots in the ends of 10 both the plates forming the lever box; the heads of these bolts spreading and holding the plates, while the bolts are loose within the slots, allowing a vertical movement to 15 the lever box.

In the head blocks S, and T: besides the head plates u, and v, which keep the lever box in its longitudinal position, there are also the transverse plates W, and X, cast 20 upon them, on which the weight of the lever box rests. Through these last mentioned plates are inserted, from beneath, the adjusting screws y, z; so that when by reason of the wear aforesaid, or from any other 25 cause the valve rods K, and L, require tightening up, raising or lowering as the case may be; in order to produce a proper closure of the valve gates; it is done by the use of these adjusting screws. The lower 30 edges of both the plates of which the lever box is made, resting on these adjusting screws, the whole box, including the bearings of the levers, is raised by the driving forward of these screws; and the reverse 35 movement lets it down again, till the required adjustment is obtained. So that

none of the machinery is taken up, or removed for this purpose. By this arrangement of the leverage, with the compact, and convenient disposition of the levers here 40 described, so as to form no obstruction to the necessary movements about the lock; and the ready adjustment here provided for of such derangements as are consequent upon the use of the gates; it is found that 45 large valve gates necessary for the speedy filling and discharge of large canal locks, may be operated with great ease, safety and economy.

What we claim as our invention and desire to secure by Letters Patent is—

1. The hooked form of the levers M, and N, and the curving of the shackle bars H, and I, as described, and for the purposes 55 described.

2. The adjustable lever-box above described, including the mode of adjusting the valve rods, and tightening the valve-gates by the use of the screws y, z, or their equivalent, as described.

3. We also claim the combination of the hooked levers with the curved shackle bars, and the adjustable lever box as described, and for the purposes described, the whole being constructed and arranged substantially in the manner, and for the purposes 65 above set forth.

GEO. W. WOOD.
LUCIUS O. WEBSTER.
